BOBBIN HOLDER

David L. Bohannon, Charlotte, N. C., assignor to Pneu-mafil Corporation, Charlotte, N. C., a corporation of Delaware

Application April 2, 1956, Serial No. 40,869

Term of patent 14 years

(Cl. D92—15)

FIG. 1.

FIG. 2.

FIG. 3.

FIG. 4.

Figure 1 represents a front elevational view of the bobbin holder in its normal operative orientation;

Figure 2 is a top plan view looking down at the bobbin holder, as seen in Figure 1;

Figure 3 is a plan view looking upward from the bottom of the bobbin holder, as seen in Figure 1; and

Figure 4 is a perspective view looking upward at the bobbin holder with the bobbin engaging portion displaced from its normally dependent bobbin engaging portion displaced to reveal the cuplike formation of the supporting structure.

What is claimed is:

The ornamental design for a bobbin holder, as shown.
